UNITED STATES PATENT OFFICE.

DAVID D. GORDON, OF CHICAGO, ILLINOIS, ASSIGNOR TO YOST ELECTRIC MANUFACTURING COMPANY, OF TOLEDO, OHIO.

SWITCHING DEVICE.

1,131,129.

Specification of Letters Patent. Patented Mar. 9, 1915.

Application filed October 5, 1911. Serial No. 652,943.

To all whom it may concern:

Be it known that I, DAVID D. GORDON, a citizen of the United States, residing at Chicago, in the county of Cook and State of Illinois, have invented a certain new and useful improvement in Switching Devices, of which the following is a full, clear, concise, and exact description, reference being had to the accompanying drawings, forming 10 a part of this specification.

My invention relates to switching devices and has for its object the provision of an improved device of this character which is of the quick break variety and in which the 15 number of parts required is reduced to a minimum.

My invention is of a broad character and can be used in a variety of different forms of switching devices, but I will herein describe two specific forms of my invention as applied more particularly to a pendant switch, although not in any way intending thereby to limit myself to such application or to the particular forms of the switching 25 devices utilized as my form of switch mechanism is adjustable to socket switches, wall switches and in fact any form of allied switch mechanism. These particular forms of my invention, I will now describe in connection with the accompanying drawing, in 30 which:

Figure 1 is a view of one of the halves of the casing showing the switch elements; Fig. 2 is a view of the same with the parts in an 35 alternative position; Fig. 3 is a sectional view on line *a—a* of Fig. 2; Fig. 4 is a sectional view on line *b—b* of Fig. 2; Fig. 5 is a sectional view of a modification; Fig. 6 is a similar view to Fig. 5, the parts being 40 shown in alternative position; Fig. 7 is a sectional view on line *c—c* of Fig. 6; Fig. 8 is a sectional view on line *b—b* of Fig. 6; and Fig. 9 is a top view with the cover removed.

My improved switch as shown in Figs. 1 to 4 is made of two halves 1 and 2 preferably of insulating material held together by means of screws 3 and 4. Within section 1 a contact element 5 and within section 2 a contact element 6 is mounted and held in place by means of screws 7 and 8 which serve at the same time to secure the ends of the entering line conductors 9 and 10 entering through the aperture 11 semi-circular 50 in each half so as to produce a circular en-

tering aperture for these wires 9 and 10. In order to make contact between the switching devices 5 and 6 I employ a ball 12, which ball when in the position shown in Fig. 2 engages the contacts 5 and 6 to close circuit 60 therethrough and when occupying the position of Fig. 1 is removed from these contact elements 5 and 6 so that the circuit through these contacts is uncompleted. In order to move the ball 12 from one position to its alternative position and vice versa through some suitable snap action, I provide a coiled spring 13 having its last convolution 14 of somewhat larger diameter than the remaining convolutions, and which 65 spring 13 has its last and enlarged convolution engaging the ball 12 by resting thereagainst. The other end of the spring 13 is held in a hole 15 provided in a plunger 16, which plunger slides to and fro horizontally 70 and occupies one or the other of its positions illustrated in Figs. 1 and 2. A projection 17 forming part of the casing 2 confines the stroke of the plunger 16. Semi-circular recesses are provided in each of the 75 halves 1 and 2 which together form a circular bore within which the plunger 16 may slide. Now assuming that the parts are in the position occupied in Fig. 1, then if it be desired to move the ball 12 into such 80 position that it engages the contacts 5 and 6, then said plunger 16 (Fig. 1) is moved toward the right until the spring 13 occupies a substantially vertical position between the ball 12 and the recess 15 and a slight further movement toward the right will immediately cause the confined spring to exert 85 its pressure to violently and quickly throw the ball 12 to the left into the position occupied in Fig. 2 and likewise exert a spring 90 action to complete the movement of the plunger 16 toward the right so that the parts then occupy the position shown in Fig. 2. Now if it is desired to open the circuit through these contact elements, then the 95 plunger 16 (Fig. 2) must be moved toward the left and the same action, but in a reverse order, takes place, namely that the spring 13 is again moved to occupy a substantially vertical position between the ball 100 12 and the aperture 15, and then a further slight movement toward the left will cause the confined spring to be liberated by offering it an opportunity to thrust the ball 12 to the right which it does at the same time 110

exerting spring pressure against the plunger 16 to complete its movement toward the left so that the parts may occupy the position of Fig. 1. It will thus be seen that by means of a very simple structure set forth herein, the plunger 16 in combination with the spring 13 is adapted to move the ball 12 violently from one position to its alternative position and vice versa. The snap action required to effect a quick break is here obtained by means of a very small number of parts and the efficacy of the contact may be readily controlled by the strength of the spring 13, likewise by the size of the exposed portions of the contacts 5 and 6.

Referring now to Figs. 5 to 9 inclusive, I show a modification in which the preferably insulating shell and body portion of the switch consists of a body portion 18 and cap 19 having screw threaded engagement therewith and a rotatable operating element 20, which rotatable operating element has a grooved portion 21 and is held in the body portion 18 by means of the U shaped form 22 whose tines project through the opposite walls of the body portion 18. The element 20 has a recess 23 to support a spring 18, which spring engages the ball 12. The terminal wires 9 and 10 again extend by means of screws 7 and 8 to contact terminals 5 and 6 which project into a runway provided for the ball 12 within a grooved portion 24 of the upper part of the body portion 18. A slight indentation at 25 is provided for the ball 12 at that portion of its stroke where it engages the terminals 5 and 6 to more thoroughly hold it in its limiting position at that point. The ball 12 thus slides transversely across the element 18 within the groove 24 and the recess 25. When the element 20 is rotated similarly to the action described in connection with the element 16, the ball 12 is moved from one of its limiting positions to the other by snap action. While that end of the spring 13 that rests within the groove 23 describes a circular motion when the element 20 is rotated, the ball 12 in response to these movements of the spring reciprocates back and forth within the groove 24 as will be clearly apparent. I

am thus enabled to get a snap action by rotating the controlling element instead of reciprocating the same as shown in the structure illustrated in Figs. 1 to 4 inclusive.

While I have herein shown and particularly described one embodiment of my invention, I do not mean to limit myself to such description and illustration, but

Having thus described one form of carrying out my invention, what I claim as new and desire to secure by Letters Patent is:

1. A device of the character described having a contact terminal, a spherical contact element for said terminal, a runway for said element, a coiled spring engaging said element, and a reciprocating plunger for controlling the free end of said spring so that a movement of said free end in one direction moves said element by snap action into engagement with said terminal and a movement in the opposite direction moves said element away from said terminal.

2. A device of the character described having a contact terminal, a slidable contact element for said terminal, a runway for said element, a coiled spring engaging said element, and a reciprocating plunger for controlling the free end of said spring to compress the same and move it beyond its position of repose to thereby move said element from either limiting position to the other by snap action.

3. A device of the character described having a contact terminal, a spherical contact element for said terminal, a runway for said element, a coiled spring engaging said element, and a reciprocating plunger for controlling the free end of said spring to compress the same and move it beyond its position of repose to thereby move said element from either limiting position to the other by snap action.

In witness whereof, I hereunto subscribe my name this 28th day of September, A. D., 1911.

DAVID D. GORDON.
